DEVICE FOR FACILITATING THE REMOVAL
OF A CORE FROM A BARRELJesse C. Wright, Los Angeles, Calif., assignor to
Globe Oil Tools Company, Los Nietos, Calif., a
corporation of California

Application May 13, 1933, Serial No. 670,837

2 Claims. (Cl. 255—1)

This invention relates to a device for use in connection with a core barrel, and relates more particularly to a device for facilitating the removal of a core from the barrel of a well core drill or core receiving well drilling tool. It is an object of the invention to provide a practical and effective device for facilitating the rapid and safe removal of a core from a core barrel.

It is sometimes difficult to safely and efficiently remove cores from the barrels of single barrel core drills and well drilling bits. The cores obtained in the barrels are often very long so that it is not practical or safe to stand the barrels on end and lift them off of the cores. In one method of removing a core from a core barrel, the barrel is laid in a horizontal position to permit the disconnection of the core catcher and bit head and is then raised from its upper end until it assumes a sufficiently inclined position to allow the core to spill or discharge from the lower end of the barrel. This manner of removing the core from a core barrel is slow and laborious, as the loaded barrel is very heavy and difficult to handle, and only comparatively short sections or pieces of the core can freely spill from the lower end of the inclined barrel.

An object of the invention is to provide a device adapted to be attached to a core barrel after it has been withdrawn from the well that allows the core to be rapidly and safely removed from the barrel without tilting or inclining the barrel.

Another object of the invention is to provide a device for application to a loaded core barrel that is adapted to carry or support the core after the core catcher and bit head have been disconnected from the lower end of the barrel to permit the core catcher and bit head to be quickly and safely removed from below the barrel when the barrel is raised.

Another object of the invention is to provide a device adapted to be attached to the lower end portion of a loaded core barrel that is operable to cut or break off the portion of the core protruding from the barrel and that supports the remaining portion of the core in the barrel to allow the broken off portion of the core to be removed.

Another object of the invention is to provide a device of the character mentioned that may act as a brake to control the downward movement of the core in the barrel so that the core may be permitted to slide slowly from the lower end of the barrel until its end strikes the derrick floor or rotary table after which the device is operable to cut or break off the protruding part of the core.

It is another object of the invention to provide a device of the character mentioned that may be easily and quickly attached to and removed from a core barrel.

A further object of the invention is to provide

a device of the character mentioned that is simple and inexpensive of manufacture and that is easy and convenient to handle and operate.

Other objects and features of the invention will be best and fully understood from the following detailed description of typical forms and applications of the invention, throughout which description reference is had to the accompanying drawings, in which:

Fig. 1 is a side elevation of one embodiment of the invention showing it arranged in operative position on a core barrel that has just been disconnected from the core catcher supporting the core. Fig. 2 is a side elevation and partial vertical sectional view of the form of the invention illustrated in Fig. 1, illustrating it in operative position on a core barrel, and in gripping engagement with the core. Fig. 3 is a top or plan view of the device illustrated in Figs. 1 and 2. Fig. 4 is a side elevation and partial vertical sectional view of another form of the invention showing it in operative position on a core barrel, and Fig. 5 is a top or plan view of the device illustrated in Fig. 4.

The device provided by the present invention may be embodied in forms for use in connection with core barrels or core receiving parts of drilling tools of various characters and sizes. Throughout the following detailed disclosure I will describe two typical embodiments of the invention employed in connection with a more or less common form of a core receiving well drilling tool, it being understood that the invention is not to be considered as restricted to the specific forms or applications about to be described, but is to be taken as including any features or modifications that may fall within the scope of the claims.

The core taking or core receiving well drilling tool illustrated in the drawings includes an elongate barrel 10 for receiving the core C and provided at its upper end with a connecting member or sub 11. The sub 11 is adapted to be connected with the lower end of an operating string of drill pipe, or the like. A sub 12 is provided on the lower end of the barrel 10 and has a downwardly projecting screw threaded pin 13. The sub 12 is of greater diameter than the barrel 10 and its upper end 14 forms an upwardly facing annular shoulder adjacent the lower end of the barrel. A tubular member 15 is normally screw-threaded on the pin 13 and carries means for catching or retaining the core C in the barrel. In the particular case illustrated in the drawings, the core catching means consists of a plurality of pivoted core gripping and supporting dogs 16 projecting from the interior of the tubular member 15. Fig. 1 of the drawings illustrates the dogs 16 in supporting engagement with the core

C after the barrel 10 has been disconnected from the member 15. A tubular bit head 17 is screw-threaded on to the lower end of the member 15. The bit head 17 is provided with a plurality of cutting parts or blades 18 operable to make an annular cut in the earth formation. The particular core receiving well drilling tool illustrated is a single barreled core receiving bit intended to be used in the rotary method of well drilling. The 10 rotary mud or circulation fluid is passed downwardly under pressure through the barrel 10 to discharge from the lower end of the tubular bit head 17. The circulation fluid flowing downwardly through the tool keeps the core C loose 15 and free so that it does not become jammed or caught in the tool.

The form of the invention illustrated in Figs. 1 to 3 inclusive of the drawings includes generally, a ring 20 adapted to be attached to or applied 20 to the barrel 10, and a clamp ring 21 connected with the ring 20 and adapted to grip the core C and to break or cut the projecting lower end portion of the core free from the portion of the core in the barrel.

25 The ring 20 is provided to carry or suspend the core engaging clamp ring 21 and is adapted to surround the barrel 10 and rest on the upper end 14 of the sub 12. In the form of the invention being described, the ring 20 includes two pivotally or 30 hingedly connected sections 22. The sections 22 are substantially semi-circular and are formed and proportioned so that they may be arranged around the barrel 10. A hinge pin or pivot pin 23 extends through vertical openings in yoked 35 parts on one section 22 and a tongue on the other section 22 to pivotally connect the sections. Outwardly projecting flanges 24 are provided on the outer or free ends of the sections 22 and a bolt 25 is adapted to be passed through openings 40 in the flanges 24 after the sections 22 have been arranged around the barrel. A nut 26 may be threaded on the bolt 25 to retain or clamp the ring 20 on the barrel 10. The lower end of the ring 20 is preferably flat to effectively seat on the 45 upper end 14 of the sub 12. It will be apparent how the ring 20 consisting of the hingedly connected semi-circular sections 22 may be readily arranged around the barrel 10 and clamped in position against the shoulder 14.

50 The ring 21 which is carried by the ring 20 is operable to support the core C and to cut or break loose the portion of the core that may project from the lower end of the barrel 10. The ring 21 includes two substantially semi-circular sections 27 pivotally connected by a hinge pin or pivot pin 28. The sections 27 are proportioned so that they are adapted to fit around the core C in the manner illustrated in the drawings. Outwardly projecting flanges 29 are provided on 55 the free or outer ends of the sections 27 and a clamp screw or bolt 30 may be passed through horizontal openings in the flanges 29. A clamp member or nut 31 is adapted to be threaded on the bolt 30 to clamp the sections 27 together on 60 to the core C.

In accordance with the invention, means is provided on the inner sides or interior surfaces of the ring sections 27 for biting into the core C to support it or break its projecting lower portion 70 away from the main core portion retained in the barrel. Wicks or teeth 33 are provided on the inner walls of the sections 27 to engage the core C. In practice, the sets of teeth 33 may be positioned so that they are diametrically opposite 75 when the ring 21 is in position around the core

C. Sufficient space or clearance is provided between the adjacent ends of the ring sections 27 and flanges 29 so that the nut 31 may be tightened to force the teeth 33 into tight holding engagement with the core and to cut or break 5 the core. Flexible elements 34 in the nature of wires, ropes, or cables 34, suspend the ring 21 from the ring 20. The flexible elements 34 are connected with the ring sections 22 and 27 by suitable eyes 35, or the like. The flexible elements 34 are sufficiently long to suspend the core engaging ring 21 in a position below the lower end of the sub pin 13 when the upper ring 20 is seated on the shoulder 14.

When the well tool has been withdrawn from 15 the well bore it may be suspended in a vertical position in the well derrick and the bit head 17 on its lower end may be permitted to rest on or engage the rotary table, derrick floor, or other suitable support. The core catcher sub 15 may 20 then be disconnected from the barrel 10, that is, the pin 13 of the sub 12 may be unthreaded from the socket in the upper end of the core catcher sub 15. The barrel 10 may then be raised a comparatively short distance to a position such as illustrated in Fig. 1 and the ring 20 is arranged around the barrel so that it rests on the shoulder 14. The sections 27 of the lower ring 21 may then be arranged around the exposed portion of the core C between the subs 12 and 15 30 and the teeth 33 of the lower ring may be forced into the core by tightening the nut 31 on the bolt 30. After the nut 31 has been tightened sufficiently to insure a proper holding engagement of the teeth 33 with the core C, the barrel 35 10, together with the device may be raised. During this raising of the barrel 10, the core is carried by the barrel so that its projecting lower end portion is lifted out of the core catcher sub 15. The core catcher sub 15 and the bit head 17 40 may then be removed from below the lower end of the core barrel 10 and the barrel 10 may be lowered until the lower end of the core C comes into engagement with the derrick floor or support. The nut 31 may then be loosened to allow 45 the teeth 33 to move out of gripping or holding engagement with the core C so that the barrel 10 may be raised without lifting the core. After the barrel 10 has been raised a suitable distance, the nut 31 may be again tightened to force the 50 teeth 33 into the core C. The lower ring 21 may be clamped or tightened so that the teeth 33 cut or break loose the projecting lower end portion of the core. This separated or detached portion of the core may then be removed. The teeth 33 55 after cutting or breaking loose the lower portion of the core C support the remainder of the core in the barrel 10. The barrel 10 may then be lowered until the lower end of the core comes into engagement with the derrick floor or support 60 so that the teeth 33 of the lower ring 21 may be disengaged from the core C permitting the barrel 10 to be raised so that the operation above described may be repeated. If desired, instead of lowering the barrel 10 the nut 26 may be loosened 65 to allow the core to slowly slide out of the barrel until its lower end engages the floor or rotary table whereupon the protruding portion of the core may be cut or broken loose by the teeth 33. It will be apparent how the entire core C may be 70 easily and quickly removed from the barrel 10 by merely raising and lowering the core 10 and tightening and loosening the lower ring 21 in the manner described above. The core C may be safely removed from the barrel 10 with little or 75

no manual handling of the barrel 10 and without tilting or inclining the barrel. The ring 20 may be very easily and quickly arranged on and removed from the barrel 10 and the device is easy and convenient to handle.

The form of the invention illustrated in Figs. 4 and 5 of the drawings includes, generally, a body or ring 40 adapted to be connected with the lower end of the barrel 10, and means 41 on the ring 40 for supporting the core C and for breaking the lower projecting portion of the core C from the portion of the core in the barrel.

The body or ring 40 is adapted to be removably attached to the sub 12 on the lower end of the barrel 10. The ring 40 consists of two substantially semi-circular sections 42 pivotally connected by a hinge pin or pin 43. Projecting meshing or overlapping parts 44 are provided on the outer or free ends of the sections 42. A removable pin 45 is adapted to be inserted in vertical openings in the overlapping parts 44 to connect the free ends of the ring sections 42. The sections 42 of the body or ring 40 are adapted to be assembled around the pin 13 of the sub 12. A thread 46 is provided on the interior of the sections 42 to cooperate with the thread on the pin 13. After the core catcher sub 15 has been disconnected from the sub 12 and the barrel 12 has been raised a short distance, the sections 42 of the ring 40 may be assembled around the core adjacent the threaded pin 13 and the pin 45 may be passed through the openings in the overlapping parts 44. The ring 40 may then be threaded on to the sub pin 13. The body or ring 40 is proportioned so that it projects downwardly beyond the lower end of the pin 13 when fully threaded on the pin.

The means 41 for supporting the core C and for cutting or breaking the lower portion of the core free from the main body of the core is provided on the projecting lower portion of the ring 40. The means 41 includes one or more screws 50 on the ring sections 42. In the particular case illustrated in the drawings there is one screw 50 provided on each section 42. The screws 50 are threaded through diametrically opposite radial openings 51 in the ring sections 42. The screws 50 project into the core receiving or passing opening of the ring 40 and their inner ends 52 are pointed so as to bite or cut into the core C. Suitable handles are provided on the projecting outer ends of the screws 50 to facilitate the easy operation of the screws. In the particular case illustrated in the drawings, T handles 53 are provided on the outer ends of the screws 50.

In employing the form of the invention illustrated in Figs. 4 and 5 of the drawings, the body 40 is adapted to be arranged around the pin 13 after the core catcher or core catcher sub 15 has been disconnected from the sub 12 and the barrel 10 has been raised. With the sections 42 of the ring 40 assembled around the pin 13, the retaining pin 45 may be arranged in the openings in the overlapping parts 44, and the ring 40 threaded on to the pin 13. The screws 50 may then be threaded inwardly so that their pointed inner ends 52 bite into the core C. When the screws 50 have been threaded sufficiently to have supporting engagement with the core C, the barrel 10 may be raised to disengage the lower portion of the core from the bit head 17 and core catcher sub 15. The core catcher sub and bit

head may then be removed from below the core barrel and the barrel lowered to allow the lower end of the core to come into engagement with the rotary table or derrick floor. When the barrel 10 is in engagement with the rotary table or derrick floor, the screws 50 may be threaded out of engagement with the core and the barrel raised a suitable distance. As the core C is free in the barrel 10 it remains stationary during the raising of the barrel. The screws 50 may be threaded inwardly to cut or break free the projecting lower end portion of the core which may then be removed. The barrel 10 may then be lowered so that the core comes into engagement with the derrick floor and the above described operation may be repeated until the entire core is removed from the barrel. If desired, the screws 50 may be threaded outwardly when the barrel is in a raised position after removal of the projecting portion of the core to allow the core to slide downwardly until its lower end comes into engagement with the derrick floor or rotary table. When the device is used in this manner, the screws 50 may operate as brakes to govern or control the downward movement of the core out of the barrel. The screws 50 may be threaded inwardly to break free the protruding portion of the core which may be then removed and the screws may again be threaded outwardly to permit the downward movement of the core from the barrel. The body or ring 40 may be quickly attached to and removed from the core barrel, and the device is simple and convenient to operate. The device is light in weight, and is compact, and provides for the quick safe removal of the core from the core barrel.

Having described only typical forms and applications of my invention, I do not wish to be limited to the specific forms and applications herein set forth, but wish to reserve to myself any variations or modifications that may appear to those skilled in the art or fall within the scope of the following claims.

Having described my invention, I claim:

1. In combination, the core receiving barrel of a well tool, and a device for facilitating the removal of a core from the barrel including pivotally connected sections adapted to be assembled around the lower portion of the barrel, screws threaded through openings in the sections and having pointed inner ends for gripping a portion of the core projecting from the lower end of the barrel, and manually engageable handles on the outer ends of the screws whereby the screws may be threaded inwardly to grip and support the core or break the core.

2. In combination, the core receiving barrel of a well tool, and a device for facilitating the removal of a core from the barrel including pivotally connected sections adapted to be assembled around the lower portion of the barrel, a thread on the interiors of the sections whereby the sections may be threaded to the barrel, screws threaded through openings in the sections and having pointed inner ends for gripping a portion of the core projecting from the lower end of the barrel, and manually engageable handles on the outer ends of the screws whereby the screws may be threaded inwardly to grip and support the core or break the core.

JESSE C. WRIGHT.
